UNITED STATES PATENT OFFICE.

ERNEST ARMSTRONG, OF CAMDEN, NEW JERSEY, ASSIGNOR, BY DIRECT
AND MESNE ASSIGNMENTS, TO UNIVERSAL CAR JOURNAL OILER
COMPANY, A CORPORATION OF SOUTH DAKOTA.

OILER FOR CAR-JOURNALS.

SPECIFICATION forming part of Letters Patent No. 714,272, dated November 25, 1902.

Application filed February 15, 1902. Serial No. 94,191. (No model.)

To all whom it may concern:

Be it known that I, ERNEST ARMSTRONG, a citizen of the United States, residing at Camden, county of Camden, and State of New Jersey, have invented a new and useful Improvement in Oilers for Car-Journals, of which the following is a full, clear, and exact description, reference being had to the accompanying drawings, which form a part of this specification.

My invention relates to oilers for car-journals. It has for its object to improve oilers of this character, and particularly of the type shown in Letters Patent No. 663,407, issued to me December 11, 1900. A serious imperfection in oilers of this class is the tendency of the surface of the pad in contact with the journal to become "glazed"—that is, to get smooth—by reason of its being held under spring-pressure in contact with the rapidly-revolving journal. For the same reason there is a tendency of the pad to be compressed, and thus rendered relatively non-porous. This condition of the bearing-surface and interior of the pad effects its capacity to take up oil and to feed it to the journal. It is also not altogether desirable to construct the supporting-springs in the manner shown in said patent, as it does not secure the desired delicacy of spring-pressure, resulting in a tendency to compress the pad by virtue of too strong pressure against the journal and making it less convenient to depress the device for the purpose of introducing and removing the pads.

The object of my invention is to remedy these imperfections.

It consists of novel means for preventing the glazing of the pad and of an improved construction of supporting-spring.

In the drawings, Figure 1 is a longitudinal vertical section of a car-axle box, showing the car-axle within the box and the lubricating device in operative position therein. Fig. 2 is a transverse section on the line 2-2 of Fig. 1. Fig. 3 is a perspective view of the lubricating device, part of the side pads and feeders being omitted for purposes of illustration. Fig. 4 is a sectional view of one of the spacers. Fig. 5 is a perspective view showing a spacer

in position on the lubricating device. Fig. 6 is a diagrammatic view showing the formation of the bottom and body of the pad and the feeders.

A is the axle.

B is the journal, turning in bearings in the journal-box C.

1 designates a plurality of curved spring-supports, having a horizontal plate 2 connected therewith at the center of length, there being a plurality of inversely-curved arms or pad-holders 3 secured upon the plate 2 and to the curved spring-supports 1 by means of rivets or screws 4. The curved arms 3 have a semicircular contour coinciding substantially or approximately with the periphery of the journal B. The parts 1, 2, and 3 form the base for supporting the pad D, to which through the wicking or feeders 6 the oil is conveyed and which by contact with the journal maintains it lubricated.

In order to increase the resiliency of the spring-supports, I form them as follows: Each support is curved upwardly and inwardly from its lower end, thence abruptly outwardly and in a gradual curve upwardly and inwardly, the top thereof or that part to which the plate 2 is secured being substantially flat. This greatly increases the resiliency of the spring over the semi-elliptical form shown in my said patent and causes the pad to press against the journal with a more delicate and yet quite sufficient pressure. At the same time it increases the compressibility in a vertical direction of the base, thus facilitating its insertion within the box.

The pad D is formed in three sections, the central section 5 resting immediately upon and over the plate 2 and the side sections 7 resting upon the ends of the curved arms 3. Extending beyond each edge of each section and secured thereto or integral therewith are feeders 6. The pad may be formed of any desired porous material capable of holding in suspension a large quantity of oil, and the feeders may consist of any material capable of conveying the oil by capillary attraction to the pad. Preferably, however, the feeders consist of a large number of thick loosely-twisted cotton or other wick threads, and

each pad-section is formed by interweaving these wick-threads together throughout a portion of their length to form the base of the pad and by projecting a number of the 5 wick-threads above the interwoven surface of the pad-section and cutting them off, so that each pad-section consists of a more or less closely-woven base and a body composed of a large number of closely-associated upwardly-projecting wick-threads, while the feeders are integral with the pad-section. By making the pad in sections, which of course may or may not be separate from each other, I am enabled to provide so large a 15 mass of wicking that it is possible to feed to the journal a quantity of oil sufficient to thoroughly lubricate it when turning at its highest speed. The outer set of feeders of the side pad-sections are somewhat longer 20 than the other feeders, so that all the feeders will project to an equal extent into the reservoir of oil at the bottom of the box. The side sections 77 are secured to the arms 3, while the central section 5 is secured, preferably, to the plate 2 between the arms 3. I have provided the following means for securing the pad to the base and at the same time prevent glazing of the pad. 25 88 are spacers having a central orifice 9 of relatively large diameter at the top and a central orifice 10 of relatively small diameter at the bottom, an annular shoulder being formed where the two orifices meet in the interior of the spacer. These spacers, which are of less 30 thickness than the body of the pad, are placed on the upper surface of the pad, and by means of suitable rivets 11, inserted into the orifices 9 and extending through the orifices 10 and the arms 3 or plate 2, the pad is secured to the 35 base and the spacers sunk into the bottom of the pad. At the same time these spacers by contacting with the journal prevent the pad from being pressed as closely as it otherwise would be against the journal. This prevents 40 the pad from being packed or compressed and its surface from becoming glazed, and thus maintains its porosity and its capacity to feed the necessary quantity of oil to the journal. 45 Having now fully described my invention, 50 what I claim, and desire to protect by Letters Patent, is—

1. An oiler for journals comprising a base, a thick capillary pad resting thereon and capillary feeders extending from said pad and

adapted to connect the pad with the oil-supply and spacers sunk into the body of the pad of a thickness less than the thickness of the body of the pad, thereby permitting the pad to contact with the journal but restricting the pressure of the same against the journal and thus preventing glazing and maintaining the capillarity of the pad. 55

2. An oiler for journals comprising a base, a pad resting thereon, and capillary feeders extending from said pad and adapted to connect the pad with the oil-supply, the pad consisting of a woven bottom and a body of closely-associated capillary threads extending upward from the bottom, and spacers secured upon the woven bottom and of less thickness than the length of the upwardly-extending threads. 65

3. An oiler for journals comprising a base, a capillary pad resting thereon, and capillary feeders extending from said pad and adapted to connect the pad with the oil-supply, spacers sunk into, and of less thickness than, the body of the pad, and securing means engaging the spacers and the base, thereby securing the pad to the base and preventing glazing of the 70 pad. 75

4. An oiler for journals comprising a base, a capillary pad resting thereon, and capillary feeders extending from said pad and adapted to connect the pad with the oil-supply, spacers sunk into, and of less thickness than, the body of the pad, the spacers having hollow interior, and securing means extending from the hollow interior of the spacer through the pad and engaging the base. 80 90

5. An oiler for journals comprising a base and an oiling-pad thereon, the base consisting of supporting-springs, plates thereon, and holders above the plates for holding the pad, the supporting-springs being curved inwardly 95 and upwardly from their lower ends, thence outwardly, upwardly, and inwardly, the top thereof being flat, and the plates being located over the flat top, and means for securing the parts of the base together. 100

In testimony of which invention I have hereunto set my hand, at Philadelphia, on this 7th day of February, 1902.

ERNEST ARMSTRONG.
